United States Patent

Des. 242,343

Patented Nov. 16, 1976

242,343

STATIONERY FOLDER

Keith Royal Testro and Rex Clifford Testro, both of 222
Queen St., Melbourne, Victoria, Australia

Filed Apr. 17, 1974, Ser. No. 461,710

Term of patent 14 years

Int. Cl. D19—04

U.S. Cl. D19—26

FIG. 1.

FIG. 2.

FIG. 3.

FIG. 1 is a perspective view of a stationery folder showing our new design;

FIG. 2 is a rear perspective view;

FIG. 3 is a perspective view of the stationery folder shown in a fully opened position.

The dashed lines shown in FIG. 3 represent a transverse seam which divides the pocket into two sections.

We claim:

The ornamental design for a stationery folder, as shown and described.
